UNITED STATES PATENT OFFICE.

FRANCIS A. WOLFE, OF SIOUX FALLS, SOUTH DAKOTA.

AUTOMATIC FIRE-EXTINGUISHER.

1,182,127.

Specification of Letters Patent.

Patented May 9, 1916.

Application filed October 5, 1915. Serial No. 54,227.

To all whom it may concern:

Be it known that I, FRANCIS A. WOLFE, a citizen of the United States, residing at Sioux Falls, in the county of Minnehaha 5 and State of South Dakota, have invented certain new and useful Improvements in Automatic Fire-Extinguishers, of which the following is a specification, reference being had to the accompanying drawings.

10 This invention comprehends certain new and useful improvements in automatic fire extinguishing devices, and relates particularly to fire extinguishers of the electrically actuated thermostatic type.

15 The invention has for its primary object a practical and very efficient apparatus of this character embodying a reservoir containing a chemical, the parts being so constructed and arranged that when a fire occurs in a room, for example, in which the device is located, the electric circuit will be automatically closed and the contents of a vial or container within the reservoir spilled into the latter, so as to produce a gas which will be sprayed out into the room and thus extinguish the fire in its incipiency.

20 The invention also has for its object a very durable and efficient construction of device of this character which may be very easily and quickly set and otherwise prepared for operation, which will be sure in its action, and not liable to get out of order or require any attention. And the invention also aims to generally improve devices of 25 this class so as to render them more useful and commercially desirable.

With these and other objects in view, as will more fully appear as the description proceeds, the invention consists in certain 30 constructions, arrangements and combinations of the parts that I shall hereinafter more fully describe and claim.

40 For a full understanding of the invention, reference is to be had to the following description and accompanying drawing, in which—

Figure 1 is a sectional view of an automatic fire extinguisher embodying the improvements of my invention. Fig. 2 is a detail plan view of the spreader plate employed. Fig. 3 is a detail view illustrating the operation of the tiltable container hereinafter specifically referred to.

Corresponding and like parts are referred 55 to in the following description and design-

nated in all of the views of the accompanying drawing by like reference characters.

Referring to the drawing, the numeral 1 designates a preferably metallic casing or reservoir, which may be of any desired shape 60 and size, according to the requirements of the case and which is shown as cylindrical, in the present embodiment of the invention. The top of the casing 1 has an upstanding plate 2 mounted thereon, said plate supporting an electromagnet 3 having an electric circuit 4 controlled by a thermostatic device of any desired character, whereby the circuit will be closed and the magnet energized, when a predetermined temperature is 65 reached or exceeded.

5 designates the armature of the magnet, said armature being provided with a shank 6 terminating at its free end in a laterally offset head 7 designed to engage a trip lever 8, the latter being provided at one end with a head 9, and a pintle 10 being passed through said head and through apertures in the upper ends of laterally spaced arms 14, whereby the lever 8 is fulcrumed in position. 75

6 The lever 8 is formed with any desired number of notches 15 designed to engage one arm of a bell crank trigger 17 pivoted at its elbow, as at 17', between the arms 14, before referred to, and the other arm of this trigger 17 is designed to extend over and engage an upwardly spring-pressed plunger 19 to hold the latter in its depressed and normal position against the tension of its spring 19'. The plunger 19 is mounted for vertical 80 movement in a screw cap 20 which is adapted to be screwed into an opening 21 formed in the top of the casing or reservoir 1, and said plunger is provided at its lower end with a preferably packed valve 22, designed to abut against the otherwise open mouth of a vial or container 23. This vial is designed to 85

90 contain a chemical which, when released in the interior of the reservoir, will, with other ingredients disposed in the reservoir, generate a gas, and the vial is detachably secured as, for example, by frictional engagement, in a preferably U-shaped clamp 24 having trunnions 25 at opposite sides; whereby it is loosely pivoted in and between the apertured ends of two depending bars 26 that extend downwardly from the bottom of the screw cap 20. Thus, it will be understood that so long as the plunger is in its lowermost position in engagement with the 95

100

105

110

vial, the latter will be held upright, but when the plunger is released, the vial will instantly be tilted by gravity, and the contents thereof will be poured into the reservoir to generate the gas, as above specified. Preferably the screw cap 20 has an angular rod 27 screwed or otherwise secured therein, said rod being capable of a turning movement, so as to extend over the upper end of the plunger 19 when the device is being set, this rod being turned out of the way after the setting operation.

Secured, as by screw-threaded engagement, in the bottom of the casing or reservoir 1 is a valve casing 28 provided with any desired number of ports 29 normally closed by a spring-pressed valve 30, and when the gas is generated, it will open this valve and the gas will be permitted to flow out through downwardly and laterally curved distributing pipes 31, of which there may be any desired number, said pipes being designed to spray the gas upon any desired number of vanes 32 formed on the upper surface of a spreader plate or disk 33 that is secured to the lower end of the stem 34 mounted for revoluble movement in the lower end of the valve casing 28.

From the foregoing description, in connection with the accompanying drawing, the operation of my improved fire extinguishing apparatus will be apparent. In the practical use of the device, after the parts are set, should an excessive temperature be reached, the circuit for the electromagnet 3 will be closed automatically, whereby the armature 5 will be drawn against the cores of the magnet and cause the head 7 to kick the trip lever 8 out of engagement with the arm 16 of the trigger 17. Thereupon the plunger 19 will be released, and the vial or container 23 will instantly tip over and pour its contents into the reservoir to generate the gas which will flow out through the distributing pipes 31 and be sprayed over a relatively large area by means of the vanes 32 and the spreader plate 33 to which the vanes are secured.

Thus it will be seen that I have provided a very efficient and automatic fire extinguishing apparatus which will require no attention at all to maintain in properly working condition, and which will instantly act as soon as a predetermined temperature is reached or exceeded.

While the accompanying drawing illustrates what I believe to be the preferred embodiment of my invention, it is to be understood that the invention is not limited thereto but that various changes may be made in the construction, arrangement and proportions of the parts without departing from the scope of the invention, as defined by the appended claims.

What is claimed, is:

1. A fire extinguishing apparatus of the

character described, comprising a reservoir, an electromagnet mounted thereon, an armature for said magnet provided with a head, means for energizing said magnet at a predetermined temperature, arms secured to the top of the reservoir, a lever fulcrumed between said arms, a trigger pivoted between said arms and engageable with said lever, a closure mounted in the top of the reservoir, arms depending from said closure, a container loosely pivoted between said arms, a plunger movable in said closure and engageable with the container to hold the latter in an upright position, the plunger being provided with a spring tending to move it away from the container, and the plunger being engageable by the trigger, whereby upon the energization of the magnet the head of the armature will engage the lever and move it out of engagement with the trigger. 85

2. A fire extinguishing apparatus of the character described comprising a reservoir, a rock arm carried by the reservoir, a trigger pivotally supported by the reservoir and engageable with the rock arm, a closure mounted in the reservoir, a container supported within the reservoir by the closure, a plunger movable in said closure and engageable with the container to hold the latter in an upright position, the trigger being also engageable with the plunger for maintaining the same in contact with the container when the trigger is operatively engaged with the rock arm, automatic means under thermostatic control for disengaging the rock arm from the trigger, and automatic means for forcing the plunger away from the container when the rock arm is disengaged from the trigger. 95

3. A fire extinguishing apparatus of the

character described comprising a reservoir, a rock arm carried by the reservoir, a trigger pivotally supported by the reservoir and engageable with the rock arm, a closure mounted in the reservoir, a container supported within the reservoir by the closure, a plunger movable in said closure and engageable with the container to hold the latter in an upright position, the trigger being also engageable with the plunger for maintaining the same in contact with the container when the trigger is operatively engaged with the rock arm, automatic means under thermostatic control for disengaging the rock arm from the trigger, automatic means for forcing the plunger away from the container when the rock arm is disengaged from the trigger, and an angular member rotatably engaged with the closure and adapted to overlie the outer end of the plunger to maintain the plunger in engagement with the container during the period required to set the trigger. 115

4. A fire extinguishing apparatus of the character described comprising a reservoir, 130

a rock arm carried by the reservoir, a trigger pivotally supported by the reservoir and engageable with the rock arm, a closure mounted in the reservoir, a container supported within the reservoir by the closure, a plunger movable in said closure and engageable with the container to hold the latter in an upright position, the trigger being also engageable with the plunger for maintaining the same in contact with the container when the trigger is operatively engaged with the rock arm, electrical means under ther-

mostatic control for disengaging the rock arm from the trigger, and automatic means for forcing the plunger away from the container when the rock arm is disengaged from the trigger. 15

In testimony whereof I hereunto affix my signature in the presence of two witnesses.

FRANCIS A. WOLFE.
